COMBINED WINDOW FRAME AND SHADE FOR AIRCRAFT CABIN INTERIOR

Richard W. Kraus, Claymont, and Jules G. Rondepierre, Wilmington, Del., assignors to Atlantic Aviation Corporation, Wilmington, Del., a corporation of Delaware

Filed Dec. 13, 1967, Ser. No. 9,764
Term of patent 14 years

U.S. Cl. D71—1
Int. Cl. D12—07

FIG. 1 is a front perspective view of a combined window frame and shade for aircraft cabin interior with representative cabin wall, window pane and chair shown in phantom outline for illustrative purposes only;

FIG. 2 is a front elevational view thereof with both shades in the retracted up position;

FIG. 3 is a right end view thereof, with the left end being identical but opposite hand;

FIG. 4 is a top plan view thereof;

FIG. 5 is a front elevational view thereof with the radially outer transparent shade drawn down;

FIG. 6 is a front elevational view thereof with the radially inner opaque shade drawn down;

FIG. 7 is a cross-sectional view taken through FIG. 6 along the line 7—7; and

FIG. 8 is a cross-sectional view taken through FIG. 5 along the line 8—8.

We claim:

The ornamental design for a combined window frame and shade for aircraft cabin interior, as shown and described.
